(57) CLAIM

The ornamental design for a shoe, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front perspective view of a shoe showing my new design; and,

FIG. 2 is a side view thereof.

The broken line immediately adjacent to and surrounding the photographic area defines the peripheral bounds of the claimed design and forms no part thereof. The broken line circle and the unshaded region therewithin form no part of the claimed design. The broken lines depicting the remainder of the shoe form no part of the claimed design.
